CLAIM

The ornamental design for a front side cover for a motorcycle as shown and described.

DESCRIPTION

FIG. 1 is a front elevational view of a front side cover for a motorcycle showing our new design; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; FIG. 7 is a front and right side perspective view thereof; FIG. 8 is a rear and right side perspective view thereof; FIG. 9 is a front and left side perspective view thereof; FIG. 10 is a rear and left side perspective view thereof; and, FIG. 11 is a reference view illustrating the environment of the front side cover for a motorcycle.

The portions of the drawings illustrated in broken lines are directed to portions of the front side cover for a motorcycle that form no part of the claimed design.

1 Claim, 11 Drawing Sheets
